US00D925495S

(12) **United States Design Patent** (10) **Patent No.:** **US D925,495 S**
Liu (45) **Date of Patent:** **** Jul. 20, 2021**

(54) **EARPHONE**

(71) Applicant: **SHENZHEN BLUE TIMES TECHNOLOGY CO., LTD**, Shenzhen (CN)

(72) Inventor: **Guangmou Liu**, Shenzhen (CN)

(73) Assignee: **SHENZHEN BLUE TIMES TECHNOLOGY CO., LTD**, Shenzhen (CN)

(**) Term: **15 Years**

(21) Appl. No.: **29/722,785**

(22) Filed: **Jan. 31, 2020**

(30) **Foreign Application Priority Data**

Aug. 13, 2019 (CN) 201930439476.9

FOREIGN PATENT DOCUMENTS

CN 306521421 * 5/2021

Primary Examiner — Paula Allen Greene*(74) Attorney, Agent, or Firm* — Li & Cai Intellectual Property (USA) Office(57) **CLAIM**

The ornamental design for an earphone, as shown and described.

DESCRIPTION

FIG. 1 is a front, right and top perspective view of an earphone showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof; and,

FIG. 7 is a bottom view thereof.

The broken lines depict portions of the earphone in which the design is embodied that forms no part of the claimed design.

1 Claim, 7 Drawing Sheets(56)
